SYNCHRONIZING APPARATUS AND SYSTEM

Erick Pearson, Chicago, Ill.

Application August 19, 1931, Serial No. 558,025
Renewed August 17, 1938

34 Claims. (Cl. 171—118)

My invention relates to synchronizing apparatus and systems and has for its object to provide an apparatus and system in which sources of alternating current may be readily synchronized and connected together.

An object of the invention resides in providing a synchronizing apparatus having a circuit making and breaking device comprising a contact making lever together with means movable in accordance with the differences of the frequencies of the two sources for operating said circuit making and breaking device.

Another object of the invention resides in providing contacts for cooperation with said contact making lever, and in further providing means movable in accordance with the differences of the frequencies of the two sources for causing relative movement between said lever and said contacts.

A still further object of the invention resides in providing a synchronizing apparatus comprising a revolute member together with a contact making and breaking device including a swinging arm having a segment thereon for engagement with said revolute member.

An object of the invention resides in providing a pivoted arm on which said first named arm swings, said pivoted arm permitting said segment to move toward and from said revolute member.

A feature of the invention resides in providing a synchronizing apparatus comprising two motors driven from the two sources to be synchronized and having relatively revolute juxtaposed parts carried contact making and breaking devices adapted to connect the sources together when the voltages thereof are in synchronism.

Another object of the invention resides in arranging said motors with the shafts thereof in axial alignment and in constructing said motors with two contacts having contacting surfaces movable in the same path of movement.

A feature of the invention resides in providing a synchronizing apparatus including two motors driven at speeds proportional to the frequencies of the sources to be synchronized and controlling the closing of a time limit closing relay for more than a predetermined time when the frequencies of the sources to be synchronized are within permissible limits so as to connect the sources together.

Another object of the invention resides in providing a synchronizing apparatus employing two motors together with segmental contacts and other contacts adapted to be brought into cooperation therewith.

A still further object of the invention resides in providing a time closing relay in conjunction with said segmental contacts and motors.

An object of the invention resides in providing 5 a synchronizing apparatus comprising two revolute members driven at speeds proportional to the speeds of the sources to be synchronized and having cooperating contacts normally out of contact making relation and in further providing 10 speed controlled means for bringing the contacts into contact making relation.

Other objects of the invention reside in the 15 novel combination and arrangement of parts and in the details of construction hereinafter illustrated and/or described.

This application is a continuation-in-part of 20 my application for patent for Automatic synchronizers, Ser. No. 695,153, filed February 26, 1924, and patented August 25, 1931, No. 1,820,319, and 25 contains subject-matter which is disclosed in my application for patent for a System for automatic parallel coupling of synchronous alternating current machines, Ser. No. 133,645, filed September 4, 1926, and patented January 30, 1934, No. 1,944,996.

In the drawings:

Fig. 1 is a wiring diagram of an electrical system illustrating an embodiment of my invention.

Fig. 2 is an elevational view of the synchronizing device illustrated in Fig. 1 with a portion of the case removed and other portions of the device shown in section.

Fig. 3 is a front elevational view of the synchronizing device shown in Fig. 2 with parts thereof 35 cut away.

Fig. 4 is a perspective view of the contact mechanism of the invention detached from the synchronizing device.

Fig. 5 is a perspective view of another of the 40 contact mechanisms of the synchronizing device shown in Fig. 2 detached therefrom.

Fig. 6 is an elevational sectional view of a modification of the contact device shown in Fig. 4.

Fig. 7 is an elevational sectional view of another form of synchronizing device.

Fig. 8 is a vertical sectional view taken on line 45 8—8 of Fig. 7.

Fig. 9 is a view similar to Fig. 8 taken on line 50 9—9 of Fig. 7.

Fig. 10 is a view similar to Fig. 9 illustrating the parts in altered relation.

Fig. 11 is a wiring diagram similar to Fig. 1 showing an installation including the synchronizing device illustrated in Fig. 7.

The invention comprises an electrical system

which is indicated in its entirety in Fig. 1. This system includes two lines, A and B, connected to sources of alternating current, or which may be portions of an alternating current net-work. Line A is illustrated as having phases indicated at 1, 2 and 3 and the line B is similarly indicated as having phases 1, 2 and 3. The two lines A and B may be connected together through a circuit breaker CB which comprises a coil CB₁ and three switches CB₂, CB₃ and CB₄ connected to the phases 1, 2 and 3 of the lines A and B.

In order to connect the two lines A and B together, it becomes necessary that the potential of the currents therein be at synchronism. For this purpose, a synchroscope indicated at N is employed which may be of usual construction and which is provided with a field 10 having a rotor 11 revoluble therein. The rotor 11 is mounted on a shaft 12 and carries suitable coils diagrammatically indicated at 13. Upon the field 10 is wound other coils 14, which serve to energize the field and to cause the rotation of the rotor 11. Inasmuch as synchroscopes are well known in the art, the synchroscope N has not been shown in detail, though it can readily be comprehended that any suitable construction may be employed. With such devices, the rotor 11 travels at a speed dependent upon the difference in frequency between the potential of currents energizing the same and in a direction depending upon which of the potentials has the greater frequency. When the frequencies are equal, the rotor 11 comes to rest at a certain locality which is always the same.

For the purpose of controlling the operation of the system, a control relay C is employed which includes a coil C₁ and two normally open switches C₂ and C₃. The coil C₁ may be connected to a control line 15 which may be energized in any suitable manner and which may be provided with a switch disposed at the control station or otherwise as desired. The control relay C controls two circuits which serve to energize the synchroscope N and also the other mechanism operating in conjunction therewith. These circuits include a common bus 16, which is connected to phases 2 of both the lines A and B. In conjunction with this common bus, another bus 17 is employed which is connected to phase 3 of line A and to the switch C₃. A similar bus 18 is connected to phase 3 of the line B and to the other switch C₂ of relay C. These circuits serve to energize the synchroscope N and the other portions of the invention as will be presently described in detail.

The synchroscope N functions in a manner to operate a synchronizing device which I have indicated at Y and which in turn serves to close the circuit breaker CB when the line conditions are proper. This synchronizing device is illustrated in Figs. 2 to 5 inclusive and will now be described in detail.

The synchroscope N is housed within a suitable case 19 which may be mounted in any suitable manner. This case has attached to it, an auxiliary case 20 which houses the synchronizing device Y and extends outwardly beyond the case 19. The case 20 consists of a shell 21 which is provided at the front thereof with a glass window 22 through which the operating mechanism of the synchronizing device may be viewed.

The synchronizing device Y utilizes the synchroscope shaft 12 which extends outwardly beyond the synchroscope proper. The shaft 12 is journalled in a bearing 25 formed in a bracket

26 secured to the case 19 and in another bearing in the synchroscope, not shown. The bracket 26 carries a circular disc or plate 27 of insulating material which is screwed to a threaded boss 5 28 at the end of the bearing 25 and which is further attached to a number of posts 29 through screws 30 screwed into said posts. Upon the shaft 12 is secured a bushing 31 of insulating material which may be keyed or pinned thereto 10 in any suitable manner. This bushing carries a spider 32 which comprises a hub 33 attached to said bushing and a flange 34 extending outwardly therefrom. A ring 35 of insulating material is secured to the flange 32 through screws 15 36, said flange being disposed within a recess 37 in the rear of said ring. Upon the periphery of the ring 35 are provided a number of contacts, one of these contacts which has been indicated at 38 is disposed toward the rear of the 20 ring and is directly connected to the flange 34 in any suitable manner. This contact has considerable circumferential extent as diagrammatically illustrated in Fig. 1. At the forward end of the ring 35 is formed another contact 39 similar to the contact 38 but of smaller circumferential extent. This contact is situated diametrically opposite the contact 38 but in a different plane from said contact. The contact 39 is connected to the spider 32 through one of the screws 25 36. Diametrically opposite the contact 39 and in the plane thereof are two contacts 41 and 42 which are rather narrow in circumferential extent and are fairly closely positioned. These contacts have attached to them, screws 43 and 44, 30 which extend into the interior of the ring 35. Two arcuate conductors 45 and 46 are secured to the screws 43 and 44, through nuts 49 and extend toward the other side of the ring. These conductors may be secured to the ring 35 through 40 screws 50 screwed therein. The ends of the two conductors 45 and 46 are provided with inwardly bent arms 51 and 52 which have attached to them outwardly extending contact pins 53 and 54, the function of which will presently be described in detail. All of the contacts 38, 39, 41 and 42 lie flush with the surface of the ring 35, being set into the outer periphery thereof at the localities illustrated.

Mounted upon the insulating disc 27 of the synchronizing device are four studs 55, 56, 57 and 58, which are constructed with threaded stems 59 extending through said disc, which stems have nuts 60 applied thereto whereby said studs may be rigidly held attached to the disc 55. The studs 55, 56, 57 and 58 are all formed with short shafts 61 projecting outwardly therefrom, which journal swinging arms 62, 63, 64 and 65. These arms are each forked at one end as indicated at 66 to receive rollers 67, 68, 69 and 70, which are rotatably mounted in said studs on shafts 71, extending through the forked portions 66 thereof. The rollers 67 and 68 are so disposed as to ride upon the periphery of ring 35 and to make contact with the contacts at 55 the rear and front of the ring respectively. The rollers 69 and 70 are similarly situated with respect to the rear and front contacts of the device and lie in the same planes as the rollers 67 and 68. The weight of the arms 62 and 63, together with the rollers thereof force said rollers into contact with the periphery of the ring 35 so as to bring the said rollers into engagement with the respective contacts as the shaft 23 rotates. The arms 64 and 65 extend appreciably 65 outwardly beyond the shafts 61 of studs 57 and 70 75

58, which extended portions serve as counterweights for raising the rollers 69 and 70 to bring the same in contact with the periphery of the ring 35 and the various contacts thereon.

For leading current to the various contacts of the ring 35, a rotary brush 72 is employed which is attached to the end of the bushing 31. This brush extends across the end of said bushing and lies along the flange 34 of the spider 32. A nut 73, screwed upon the end of the shaft 23 and engaging an insulating washer 74, forces the spring brush 72 into engagement with spider 32 thereby forming an electrical connection between said brush and spider, insulated from the shaft 12. Operating in conjunction with the rotary brush 72 is a fixed contact 75 coaxially disposed with respect to the axis of the shaft 12. This contact is provided with a threaded stem 16, which extends through a bracket 77 attached to the disc 27 through a number of bolts 78. The contact 75 engages the brush 72 thereby leading the current to the spider 32 and to the various contacts connected therewith.

Contact 75, as best shown in Fig. 2, is formed with a portion 79 which serves as a shaft and which has rotatably mounted upon it, a collar 80. This collar is of such dimensions as to frictionally engage said portion 79 and to remain in any position therein in which it is left. The collar 80 has a contact finger 81 issuing outwardly therefrom which is disposed between the two contact pins 53 and 54 and which may engage either thereof depending upon the direction of rotation of shaft 12. When shaft 12 rotates in a clockwise direction as viewed in Fig. 3, contact finger 81 is brought into engagement with contact pin 53. When said shaft is rotated in the opposite direction, contact finger 81 is brought into engagement with contact pin 54.

Operating in conjunction with the insulating bushing 31 of the synchronizing device, is another circuit closing mechanism which is shown in detail in Fig. 5. An arm 82 is pivotally connected through a pin 83 with a forked arm 84 which is pivoted on the shaft 61 of stud 56. This arm 84 is disposed between the arm 63 previously referred to and the shoulder formed on said stud. The swinging arm 82 has attached to the lower end thereof a short segment 85 which is disposed between two flanges 86 and 87 formed on the bushing 31 and which rides on a circular portion 88 of said bushing therebetween. The weight of the arm 84 and the arm 82 causes the segment 85 to contact with the portion 88 of bushing 31 thereby providing a frictional driving connection therebetween causing the arm 82 to swing in one direction or the other depending upon the direction of rotation of the shaft 12. The upper end of the arm 82 has attached to it, two contacts 89 and 90 which are adapted to engage other contacts 91 and 92 secured to posts 93 and 94 mounted on the insulating disc 27 the same as the studs 55, 56, etc., previously referred to. When the shaft 12 rotates in one direction, the contact 90 is brought into engagement with contact 92 to complete a circuit to be presently described and when the shaft 12 rotates in the opposite direction, contact 89 is brought into engagement with the contact 91. In the operation of the synchronizing device Y, the rollers 68 and 70 successively engage the contacts 39, 41 and 42. These contacts and the respective rollers serve as switches which for the sake of convenience will be described as follows. The switch procured through roller 68 and con-

5 tact 38 will be designated as Y3 and the switches secured through the contacts 41 and 42 and roller 70 will be designated as Y2 and Y1. In like manner the rollers 67 and 69 successively engage the contact 38 completing circuits to be presently described. The contact in between roller 69 and contact 38 will be designated as switch Y4 and the switch procured through the contact of roller 67 and contact 38 will be referred to as Y5.

10 In conjunction with the synchronizing device Y, a number of relays are employed which are indicated by the reference characters X, T and S. The relay X is in the nature of an auxiliary relay and serves to directly operate the circuit breaker CB. This relay comprises a coil X1 and two normally open switches X2 and X3. The relay T is a time controlled relay being provided with a coil T1, a normally open switch T2 and a timing device such as a dash pot T3. This relay is so constructed that the same operates to procure the timed closing of the switch T2 upon energization of the coil T1, and an instantaneous opening thereof upon deenergization of the coil T1. The relay S is a safety relay employed with the invention for preventing closure of the circuit breaker before the synchronizing device has had an opportunity to start. This relay includes a coil S, and three normally open switches S2, S3 and S4.

20 The various parts of the invention are connected together as follows: The synchroscope N is provided with a reactance 95 and a resistance 96 which are connected together and to a conductor 97 which is connected to switch C2 of relay C. The reactance 95 and the resistance 96 are respectively connected to the proper windings of the coil 13 through conductors 98 and 99, which windings are further connected together and to a common conductor 100, which in turn is connected to the common bus 16 of the system. The coil 14 of the synchroscope is connected through a conductor 101 with the common bus 16 and is further connected through a conductor 102 with the switch C3. When the relay C is operated, both switches C2 and C3 are closed and current is had from both lines A and B to operate said synchroscope. This rotates the rotor 11 of said synchroscope causing the shaft 12 to rotate in one direction or the other depending upon which of the lines has the higher frequency and at a rate depending upon the ratio of the frequencies of the two lines.

25 The synchronizing device Y is connected as follows: Both of the contacts 38 and 39 are connected to the revoluble brush 72 through spider 32 while the two contacts 41 and 42 may be alternately connected to the pin 81 which is connected with contact 75. Contact 75 is connected through a conductor 107 with switch C3 through conductor 102. Upon closing switch C3, energy is had from line A to energize the circuits through the synchronizing device. Roller 67 is connected through a conductor 105 with coil S1, which is connected through another conductor 103 with the common bus 16. Roller 69 is connected through a conductor 104 with switch S3, which switch is further connected through a conductor 105 with coil T1 of relay T. Conductor 106 connects this coil with the common bus 16. Before the synchronizing device is started, the contacts thereof usually remain in the position shown in Fig. 1. No current flows through the switch Y4, inasmuch as the switch S3 in series therewith is open prior to

the operation of safety relay S. As soon as shaft 12 has rotated sufficiently to bring roller 67 into engagement with contact 38, the following circuit is completed. Commencing with bus 17 current flows through switch C3, conductor 102, conductor 107, contact 75, rotary bush 72, spider 32, switch Y5, conductor 165, coil S1, and conductor 103 to the common bus 16. This energizes coil S1 and operates relay S. Energization of this relay completes two new circuits. One of these circuits includes a conductor 108 connected to switch S2 and coil S1 and another conductor 110 connected to the switch S2 and to the conductor 107 previously referred to. The circuit through the conductor 108, switch S2 and conductor 110 serves as a maintaining circuit for maintaining the relay S1 operative which remains operated as long as relay S is energized. As soon as the circuit through switch T2 is closed, relay S continues energized and the switch S3 is closed and so held. Closure of this switch prepares the following circuit. Commencing with the bus 17, the circuit extends through switch C3, conductor 102, conductor 107, contact 75, rotary brush 72, switch Y4 (now open), conductor 104, switch S3, conductor 105, through coil T1 of relay T and through conductor 106 to the common bus 16. As shaft 11 continues its rotation, contact 38 engages roller 69 and the switch Y4 is closed this operation occurring when the voltages of the currents of the two lines are approaching synchronism. The relay T then commences to operate, the dash pot T3 timing the operation thereof. If the shaft 12 is traveling slow enough, which occurs when the two frequencies of the two lines are substantially in synchronism, switch T2 will be closed, before the switch Y1 or Y2 closes. In such event, another circuit is established through switch T2. This circuit is as follows: Commencing with the contact 75, which as previously described was connected to bus 17, current would flow through the finger 81 and one or the other of the pins 53 or 54. Current would then flow through the respective conductor 45 or 46, the corresponding contact 41 or 42 and the roller 70. From there, current would travel through the conductor 111, switch T2, conductor 112, coil X1 and conductor 113 to the common bus 16. This would energize relay X, which as stated, is an auxiliary relay. The relay X, if energized for a sufficient length of time, will close the circuit breaker. The circuit therefore includes conductor 111, switch X3, conductor 118, coil CB1 and conductor 119. As soon as switch X3 is closed, the circuit breaker CB tends to close. However, the contacts 41 and 42 are relatively short in peripheral extent and under ordinary conditions the time during which said contacts remain closed is insufficient to cause the operation of the circuit breaker. To cause the actual closing thereof, a maintaining circuit is provided for relay X, which includes switch X2, conductor 115, switch Y3 and conductor 107. This circuit shunts the switch Y1 or Y2. The contact 39 of switch Y3 is considerably longer than either of the contacts 41 and 42 and hence maintains the circuit through the coil X1 of relay X closed a sufficient length of time to permit of the closing of circuit breaker CB unless the frequency difference increases substantially, in which case the shaft 12 speeds up and breaks the maintaining circuit for relay X before the circuit breaker can operate. If the circuit breaker closes, the shaft 12 stops in known

manner, with the associated parts in the position in which they are shown. This is due to the characteristic operation of the synchroscope N which, of course, will also return the apparatus Y to the position shown if it should drift slightly past this position as the circuit breaker closes. It will be noted that the two contacts 41 and 42 cause the closing of the circuit breaker closing circuit in advance of synchronism. This is for the purpose of giving the circuit breaker an opportunity to close so that closing may occur when the frequencies of the two lines are in absolute synchronism. By means of fingers 81, 53 and 54, such action may be had for both directions of rotation of the shaft 12. The circuit breaker then remains energized until the circuit 15 is again opened.

In the event that the frequencies of the two lines A and B are in exact synchronism when said lines are to be connected together, the synchroscope N would not rotate and the switch Y5 would not close to put in operation the circuit breaker closing mechanism. To overcome this disadvantage, relay L is employed. This relay comprises a coil L1, a normally open switch L2 and a timing mechanism L3 adapted to time the closing of switch L2 but to permit of the rapid opening thereof. Switch L2 is connected through a conductor 167 with conductor 112, and through a conductor 168 with conductor 115. This switch is further connected to coil L1 through conductor 169, which coil is connected to phase 1 of line B through a conductor 170. If the synchroscope N fails to rotate, a circuit is established through switch Y3 and coil L1 is energized. This circuit commences with phase 1 of line B, and includes conductor 170, coil L1, conductor 169, 168, and 115. Said circuit further includes switch Y3, brush 72, contact 75, conductors 107, 102, switch C3 and bush 17 terminating at phase 3 of line A. Since opposite phases of the two lines are employed, voltage is had for operating the relay at synchronism. If energization is maintained for a sufficient length of time, switch L2 is finally closed. This completes a circuit through coil X1 which operates the circuit breaker closing relay X. If the synchroscope N rotates the circuit through coil L1 is broken before relay X is operated and closure of the circuit breaker can only be procured through operation of the synchronizing apparatus Y as previously brought out.

In Fig. 6, I have shown a somewhat different type of contact device which may be used in place of the structure shown in Fig. 4. In this form of the invention, a cylindrical cam 120 of insulating material is employed which is attached to the shaft 12. This cam is formed with a hump 121 thereon projecting outwardly beyond the periphery thereof. Upon the disc 27 is mounted a bracket 122 which carries an adjusting screw 123 movable in a direction toward and from the shaft 12. This screw has attached to the end thereof, a bearing block 124, which has pivoted to it through a pin 125, a swinging arm 126. Arm 126 is adapted to be engaged by the hump 121 of cam 120 and to be swung about its pivot 125. The arm 126 has attached to it, a contact bar 127 which is provided with a contact 129 at its outer end adapted to engage a fixed contact 130, mounted on disc 27. The contact bar is yieldingly held attached to the arm 126 through a spring 128 and two bolts 131 and 132 loosely passing through said bar and arm. When the arm 126 is engaged by the hump 121,

contactor bar 121 is moved until the contact 129 thereof engages contact 130. Further movement of the lever 126 is permitted through the spring 128 which allows said lever to move away from the bar 121. The two contacts 129 and 130 are connected to the coil T1 and to the conductor 107. When this device is employed, the switch T2 is directly connected to conductor 107 and to synchronizing device Y, and relay S is dispensed with. When the contacts 129 and 130 remain closed for a sufficient length of time to operate timed relay T, the circuit through switch T2 is closed and the coil XI is energized the same as in the other form of the invention. By the adjustment of the screw 123, any length of time can be had through the engagement of the hump 121 with lever 126 so that the said device can be caused to function in identically the same manner as the synchronizing device Y.

In Figs. 7 to 10, I have shown a construction which may be used in place of the synchronizing device Y and the synchroscope N. This device comprises two motors 133 and 134 which are preferably mounted upon a single base 135 with the shafts 136 and 137 thereof in axial alignment. Motors 133 and 134 may be of synchronous type or any other suitable type in which the speed thereof depends upon the frequency of the voltages of the current for operating the same. The motor 133 has attached to the shaft 136 thereof, a hub 138 constructed of insulating material which is formed with a flange 139 extending outwardly from the outer end of the same. The shaft 137 has similarly attached to it, a hub 140 which is provided with a flange 141 similar to the flange 139. The flange 141 has attached to it an annular ring 142 which extends over toward the flange 139. In the end of the hub 138 is mounted a shaft extension 143 which is axially disposed with reference to the shaft 136 but is insulated therefrom. This shaft is provided with a set screw 144 for holding the same in place. Rotatably mounted upon the shaft extension 143 is a hub 145 which carries a collar 146 similar to the collar 80. This collar has attached to it a pin 147 which is adapted to engage either of two contacts 148, secured to the flange 141 and corresponding in function to the pins 53 and 54 of the device shown in Fig. 4.

The flange 139 carries two posts 149 and 150, which swingably support two arms 151 and 152 carrying rollers 153 and 154 similar to the arms and rollers of the other form of the invention, which rollers are held away from the ring 142 through springs 209. The two rollers 153 and 154 lie in different planes and are adapted to engage contacts on the inner surface of the ring 142 which are likewise disposed in two planes corresponding to the planes of said rollers. The roller 153 may engage two short closely spaced contacts 41 and 42 while the roller 154 is adapted to engage a long contact 156 diametrically opposed to the contacts 41 and 42. Current is led to the various rollers and other contacts of the device through a number of collector rings 158, 159 and 160, which are mounted on the hub 138 and through another set of collector rings 161, 162 and 163 which are mounted on the hub 140. Brushes of any type may be used in conjunction with these collector rings and serve to conduct the current through the various contacts as will now be described in detail.

The form of the synchronizing device shown in Figs. 7 to 10 is connected in a system in much

the same manner as shown in Fig. 1. Such a system is shown in Fig. 11. For this reason, the same reference characters have been employed to indicate corresponding parts of the system and only such new reference characters employed as are required to designate the parts not shown in the structure illustrated in Fig. 1. In this form of the invention, the relay S is dispensed with, since the rollers employed do not travel in the path of contact of the segmental contacts until after the motors driving the same have come up to speed. There would hence be no danger of closing of the system when the device comes to rest at its previous position at which synchronism occurred. The relay L may or may not be employed as desired. For the purpose of simplicity, this relay has also been shown as omitted from Fig. 11.

The two motors 133 and 134 are employed in place of the synchroscope N. These motors are both connected to the common bus 16 and are further connected through the conductors 97 and 102 with the two switches C2 and C3. When the relay C is actuated through energization of line 15, both the motors 133 and 134 are actuated and rotate in the same direction, each receiving its power from the respective source A or B with which it is connected.

The various contacts actuated through the two motors 133 and 134 are connected as follows. Roller 153 is connected through a conductor 200 with collector ring 158. The two contacts 41 and 42 are connected through conductors 201 and 202 with the two pins 148 and are further connected through conductors 203 and 204 with the two collector rings 162 and 163. The contact pin 147 is connected through a conductor 205 with collector ring 160. Roller 154 is connected through a conductor 206 with collector ring 159, while contact 156 is connected through a conductor 208 with collector ring 161. The brush associated with collector ring 158 is connected to conductor 111, which is connected to switch T2, and the brush associated with collector ring 159 is connected through the conductor 104 with coil T1. Conductor 107 is connected to conductor 102 and is in turn connected to the brush associated with collector ring 160. Collector ring 161 is similarly connected through a conductor 107A with conductor 102. The brushes associated with the two collector rings 162 and 163 may be connected to a suitable indicating device such as is shown in Fig. 1, or to a suitable speed matching device.

The operation of the form of the invention shown in Fig. 11 is substantially the same as that shown in Fig. 1. When the parts are at rest, the springs 209 hold the rollers 153 and 154 out of the path of movement of contacts 41, 42 and the contacts 156. When the line 15 is first closed, the circuits through the various rollers 153 and 154 are open and closure of the circuit breaker is prevented. When relay C is operated, switches C2 and C3 are closed, which energizes the two motors 133 and 134 causing the same to travel in the same direction. As soon as the motor 133 comes up to speed, the two rollers 153 and 154 are urged through centrifugal force against the inner surface of the ring 142. The functioning of the various apparatus for the closure of the circuit breaker is now possible and the synchronizing apparatus operates in much the same manner as previously described. As the roller 154 passes contact 156 it closes the circuit which energizes relay T. When the relative speed be-

tween the two members 142 and 139 is slow enough, which occurs when the frequencies of the voltages of the two sources to be synchronized are at substantially synchronism, the switch T2 is closed. The circuit for energizing relay X includes switch T2 and also the roller 153 and one or the other of the contacts 41 or 42. When the roller 153 comes in contact with the appropriate contact 41 or 42, which is determined by the rotation of the shaft and by the engagement of the pin 147 with one or the other of the pins 148, the circuit is completed through coil X1 and relay X is energized. This closes switch X3 which energizes coil CB1 of the circuit breaker CB, operating the same. By means of the two contacts 41 and 42, advance closing of the relay X may be had so that when the circuit breaker actually connects, the two sources are in synchronism. The pin 147 engages one only of the two contacts 148 at one time so that only one of these, namely the one operable in advance of synchronism is capable of closing the circuit to operate the circuit breaker. The switch X2 in the form of the invention shown in Fig. 11 is connected through conductor 166 with coil X and is further connected through a conductor 210 with the conductor 102, previously referred to. As soon as the relay X operates, the circuit is maintained through coil X1 by means of this switch which causes the said auxiliary relay to remain closed throughout the subsequent connection of the two sources together and until the circuit 15 is manually opened.

Where advance closing is not needed, the two contacts 41 and 42 may be dispensed with and a single contact 155 employed in place thereof as shown in Fig. 10. Such contact would in such case be connected directly to conductor 208 which is common with conductors 205, 107, 107A and 102.

The mechanism shown in Fig. 5 is preferably used for indicating which of the two sources of current has the greater frequency. If desired, however, the same may be used for matching speed as outlined, in other of my applications for patent now issued as Patents Nos. 1,944,996 and 2,073,426. This device is illustrated in Fig. 1 at 82, and the two fixed contacts thereof are designated at 81 and 82. These parts are connected as follows. The arm 82 is connected through a conductor 211 with switch S4 which in turn is connected through a conductor 212 with common bus 16. Contact 81 is connected through a conductor 213 with a resistance 214 and the contact 82 is connected through a conductor 215 with a resistance 216 of different value. These two resistances are connected through a common conductor 217 with an ammeter 218, which in turn is connected through a conductor 219 with conductor 18 previously referred to. Ammeter 218 through the two resistances 214 and 216 indicates which of the two sources has the higher frequency. If the sources of power are desired to be automatically regulated, speed matching may be procured by connecting the suitable speed matching mechanism to the conductors 213 and 215 in place of the ammeter 218. The same results may be procured with the form of the invention shown in Fig. 11 by connecting the speed matching apparatus to the brushes associated with the two slip rings 162 and 163.

The system shown in Fig. 1 is capable of use for the connection of a dead line directly to a live line. This is accomplished through two relays VA and VB. The relay VB includes a coil VB1

and a normally closed switch VB2. Relay VA includes a coil VA1 and a normally open switch VA2. These relays are connected as follows. Coil VB1 is connected through a conductor 218 with phase 3 of line B, and is further connected through a conductor 220 with the common 16 which is connected to phase 2 of line B. Switch VB2 is connected through a conductor 221 with conductor 102 and is further connected through a conductor 222 with switch VA2. Switch VA2 is in turn connected through a conductor 223 with conductor 166, previously referred to. Coil VA1 is connected through a conductor 224 with phase 3 of line A and through a conductor 225 with the common 16.

When the two lines A and B are both deenergized, neither of the relays VA or VB are operated, and of course, no current is to be had for closing the circuit breaker. With both lines are energized, switch VA2 is closed but switch VB2 is opened so that the circuit through these switches is broken and nothing occurs. If the line B is completely deenergized, switch VB2 closes and a circuit is established through the coil X1 of relay X, which directly closes the circuit breaker CB. The opening of circuit 15 breaks the circuit through switches VB2 and VA2 and opens the circuit breaker.

Changes in the specific form of my invention is herein disclosed may be made within the scope of what is claimed, without departing from the spirit of my invention.

Having described my invention, what I claim as new and desire to protect by Letters Patent is:

1. In an electrical system wherein two sources of alternating electromotive forces are to be connected, synchronizing means therefore comprising a revoluble member rotated in a direction and at a rate dependent upon the frequency difference of said sources, a pivoted lever, a segment on said lever adapted to be engaged by said revoluble member for swinging said lever in either direction depending upon the direction of rotation of said member, independent contacts closed by said lever upon movement of said member in opposite directions, contact means rotated with said revoluble member, cooperating contacts engaged by said contact means during the rotation thereof, and circuit means controlled by said contact means and contacts and selectively energized through said independent contacts for indicating the frequency relationship of the electro-motive forces of said sources.

2. In electric synchronizing apparatus for two sources of alternating current, the combination with two motors driven at speeds proportional to the frequencies of the sources to be synchronized, main switching means for connecting said sources, a pair of contacts, one thereof being rotated by the rotor of one motor and the other being rotated by the rotor of the other motor, said contacts having contacting surfaces traveling in the same path, a second pair of contacts similarly operated by said motors, a time limit closing relay, a switch circuit controlled by said relay for closing said main switching means, one pair of contacts acting to close the energizing circuit of said time limit closing relay for more than the time predetermined thereby when the frequencies of the sources to be synchronized are within a permissible limit of difference and the other acting to close said switch circuit when the phase relationship of the sources is correct, and devices actuated by one said motor according to its speed for maintaining at least one

said pair of contacts open until said one motor attains a predetermined speed.

3. An electric synchronizing apparatus for two sources of alternating current, comprising two motors driven at speeds proportional to the frequencies of the sources to be synchronized, main switching means for connecting said sources, a pair of contacts, one thereof being rotated by the rotor of one motor and the other being rotated by the rotor of the other motor, said contacts having contacting surfaces traveling in the same path, said contacts controlling a circuit containing a time limit closing relay, the length of the contacting surface of one of said contacts being such that when the frequencies of the two sources to be synchronized are within permissible limits the relay circuit is closed for a time sufficient to allow the relay to operate, a second pair of contacts similarly operated by said motors controlling a switch operating circuit in which circuit is a gap closed by the operation of the relay, and devices actuated by one said motor according to its speed for maintaining at least one said pair of contacts open until said one motor attains a predetermined speed.

4. In electric synchronizing apparatus for two sources of alternating current, the combination with two motors driven at speeds proportional to the frequencies of the sources to be synchronized, main switching means for connecting said sources, a pair of contacts rotatable with the rotors of said motors, and including a segmental contact, a second pair of contacts rotatable with the rotors of said motors and including another segmental contact, a circuit including said first pair of contacts and a source of power, a time closing relay in said circuit, a second circuit including said second pair of contacts and a source of power, a main switch operating coil in said second circuit and a gap in said second circuit controlled by said relay, and devices actuated by one said motor according to its speed for maintaining at least one said pair of contacts open until said one motor attains a predetermined speed.

5. In an electric synchronizing apparatus for two sources of alternating current, the combination with two motors driven at speeds proportional to the frequencies of the sources to be synchronized, main switching means for connecting said sources, two pairs of contacts rotatable with the rotors of said motors, each pair including a segmental contact, a time limit closing relay, a switch circuit controlled by said relay for closing said main switching means, one pair of said contacts acting to close the circuit of said time limit closing relay when the frequencies of the sources to be synchronized are within permissible limits and the other pair of contacts acting to close said switch circuit when the phase relationship of the sources is correct, and devices actuated by one said motor according to its speed for maintaining at least one said pair of contacts open until said one motor attains a predetermined speed.

6. A synchronizing apparatus comprising two revolute members adapted to be driven at speeds proportional to the frequencies of the sources to be synchronized, a contact carried by one of said revolute members and traveling along a defined path, a contact for engagement with said first contact and carried by the other rotary member, said second contact being normally out of the path of movement of said first contact, and speed controlled means for bringing

7. A synchronizing apparatus comprising two revolute members adapted to be driven at speeds proportional to the frequencies of the sources to be synchronized, two contacts carried by one of said revolute members, a third contact carried by said other revolute member and movable between said first contacts and adapted to contact with either thereof, means for yieldingly supporting said third contact relative to said second revolute member to cause relative movement between said third contact and the corresponding revolute member when said third contact engages either of said first contacts.

8. In an electrical system wherein two sources of alternating electromotive forces are to be connected together, a revolute member movable in accordance with the differences of the frequencies of the two sources to be synchronized, a contact lever eccentrically pivoted with respect to said revolute member, means on said revolute member for successively and momentarily swinging said lever at predetermined times in its cycle of movement, contacts opened and closed by said lever, means for varying the pivot point of said lever whereby to regulate the period during which said contacts are closed for each revolution of said member, and means controlled by said contacts for connecting the sources together.

9. In an electrical system wherein two sources of alternating electromotive forces are to be connected together, a revolute member movable in accordance with the differences of the frequencies of the two sources to be synchronized, a contact lever, a cam operated by said revolute member and engaging said lever for swinging the same, contacts opened and closed by said lever, a movable pivot for said lever, means for varying the pivot point of said lever whereby to regulate the period during which said contacts are closed for each revolution of said member, and means controlled by said contacts for connecting the sources together.

10. In an electrical system wherein two sources of alternating electromotive forces are to be connected together, a synchronizing device including a member adapted to occupy different positions dependent upon the phase relation of the sources, a lever, means on said member adapted to swing said lever at one of the positions of the member, a movable pivot for said member, means for varying the pivot point of said lever whereby to regulate the period during which said contacts are closed for each revolution of said member, contacts adapted to be opened and closed by said lever, and means controlled by said contacts for connecting the sources together.

11. In an electrical system wherein two sources of alternating electromotive forces are to be connected together, a synchronizing device including a member adapted to occupy different positions dependent upon the phase relation of the sources, a lever, contacts adapted to be actuated by said lever, means operated by said member for moving said lever to procure actuation of said contacts at one of the positions of said member, a pivot for said lever, means for varying said pivot for changing the duration of closing of said contacts for each revolution of said member, and means controlled by said contacts for connecting the sources together.

12. In an electrical system wherein two sources of alternating electromotive forces are to be connected together, motive means energized by the two sources and including a revoluble member, a contact lever eccentrically pivoted with respect to said revoluble member, means on said revoluble member for successively and momentarily swinging said lever at predetermined times in its cycle of movement, contacts opened and closed by said lever, means for varying the pivot point of said lever whereby to regulate the period during which said contacts are closed for each revolution of said member, and means controlled by said contacts for connecting said sources together.

13. In an electrical system wherein two sources of alternating electromotive force are to be connected, synchronizing means therefor comprising a revoluble member adapted to rotate continuously in either direction, a vertical lever having a segment adapted to rest on said revoluble member, a horizontal arm pivoted to said lever and swingable to guide the segment for movement toward and from the revoluble member, contacts operable by said lever and means operable by both of said sources for rotating said revoluble member.

14. In an electrical system wherein two sources of alternating current are to be connected, main switching means for connecting said sources, a first motor connected for supply by one said source, a second motor connected for supply by the other said source, circuit closing devices actuated by one of said motors when said motor has attained a predetermined speed, further circuit closing devices actuated by both said motors and operated when said sources are at small ranges of frequency and phase differences, and circuit means controlled by both said circuit closing devices for closing said main switching means.

15. In an electrical system wherein two sources of alternating current operating in substantial synchronism and having at least three phase conductors are to be connected, means for connecting a first phase conductor from one source with the corresponding phase conductor of the other source, main switching means for connecting at least the other phase conductors of said sources; a relay having an energizing coil, a switch, means for rapidly returning said switch to open position, and timing means for delaying the closing of the switch; circuit means for connecting a second phase conductor of one said source to the third phase conductor of the other said source and including said coil; and means energized by the closing of said relay switch for closing said main switching means, whereby the sum of the voltage between the said first phase conductor connecting means and the second phase conductor of said one source and the voltage between said first phase conductor connecting means and the third phase conductor of said other source is utilized for energizing said coil, said sum being a maximum when the two sources are in phase.

16. In an electrical system including two networks each supplied by a source of alternating current, main switching means for connecting said networks together, a synchronizing means responsive to differences of frequency and phase in said networks and circuits controlled thereby for closing said main switching means within a predetermined range of difference of frequency

and phase, control switch means, a relay responsive to a voltage in one said network and including contacts which are closed when said voltage does not exist therein, and circuit means independent of said synchronizing means and including said contacts and control switch means and connected for energization by the other said network for closing said main switching means when no synchronizing current is available from said one network.

17. In an apparatus for connecting two alternating current systems at least one of which varies in frequency, the combination of a main switching means for connecting said systems and having an actuating coil, a common supply conductor connected to first like conductors of said systems, a remotely controlled line, a control relay actuated by said remotely controlled line when the latter is energized, said control relay having two switching means, synchronoscope devices, two actuating circuits for said synchronoscope devices which are independently connectable through said two switching means to second like conductors of said systems, a timing relay and an energizing circuit connecting the same to said common conductor and through the synchronoscope devices to one of said second conductors, a closure relay and an energizing circuit connecting the same to said common conductor and through contacts of said timing relay and the synchronoscope devices to one of said second conductors, actuating circuit means from said common conductor through contacts of said closure relay and said actuating coil to one said second conductor, second contacts means closed by said closure relay when energized, and a maintaining circuit for the closure relay from said common conductor through said second contact means and contacts of said control relay to the one of said actuating circuits connected with said variable frequency system so that the maintaining circuit will pass out of operation when either said variable frequency system or said remotely controlled line is deenergized, said synchronoscope devices operating through said timing and closure relays to effect closing of said main switching means within a predetermined range of frequency and phase differences of said systems.

18. In an electrical system including two sources of alternating current, main switching means for connecting said sources together, and a plurality of means for closing said main switching means; one of said closing means including synchronizing devices for establishing the closing when the two sources are within a predetermined range of phase and frequency relations, another of said closing means being operated from one said source only; and selecting means responsive to voltage in the other said source operating to connect said one closing means for operation when voltage from said other source is delivered thereto, and operating to connect said other closing means for operation when voltage is not delivered from said other source.

19. In an electrical system including two sources of alternating current, main switching means for connecting said sources together, means for closing said main switching means, said closing means including synchronizing devices operated from both said sources when both are energized for establishing the closing within a predetermined range of frequency and phase relations, and devices connected to one said

source and operative when said one source is de-energized for directly establishing the closing regardless of the actuation of said synchronizing devices.

20. In an electrical system including two lines of conductors, switching means for connecting said lines, said lines conducting electrical currents having the same frequencies but at varying phase relation at said switching means, frequency and phase difference responsive means for closing said switching means including first devices for initiating the closing within a predetermined range of angles of phase difference when the frequencies of currents in said lines are identical, and devices connected for operation through one said line and effective when said one line is de-energized for initiating the closing of said switching means independently of an operation of said responsive means.

21. In an electrical system including two independently supplied lines of conductors, switching means for connecting said lines, means responsive to the electrical relation of the potentials in said lines and operative at a predetermined range of such electrical relation for initiating a closing of said switching means when both lines are charged, a relay having normally open contacts and connected to one line to be closed by current therefrom, a relay having normally closed contacts and connected to the other said line to be opened by current therefrom, and circuit means including contacts of both said relays and connected for initiating a closing of said switching means when said one line is charged and said other line is uncharged.

22. In an electrical system including two lines of conductors independently chargeable with alternating current, switching means for connecting said lines, means responsive to the frequency and phase relation of the potentials in said lines when said lines are charged and including first devices for initiating a closing of said switching means within predetermined ranges of frequency and phase differences, said responsive means also including second devices for initiating a closing of said switching means within a different range of phase difference when the frequencies are identical, and third devices responsive to the conditions of charging of said lines for initiating a closing of said switching means independently of said first and second devices when one said line is uncharged.

23. In combination with two alternating current circuits and a switch for connecting the circuits, control means for said switch including means connected and arranged to be effectively energized in accordance with the voltages incident to said circuits for effecting the closing of said switch only under predetermined electrical conditions when said means are effectively energized by said two alternating current circuits, and for closing said switch when said means is effectively energized by only one of said circuits and the other circuit is de-energized.

24. In combination with two alternating-current circuits and a switch for connecting the circuits, control means for said switch including relay means, means for effectively energizing said relay means in accordance with the voltages incident to said circuits only when said circuits are energized for effecting the closing of said switch under predetermined electrical conditions, and means operatively associated with said first means and said switch for effecting the closing

of said switch when only one of said circuits is energized.

25. In combination with two alternating-current circuits and a switch for connecting the circuits, control means for said switch including a plural element relay means connected and arranged to be energized in accordance with the voltages incident to said circuits for effecting the closing of said switch only during predetermined phase and frequency relations between the two circuit voltages and means electrically associated with said control means and said switch for effecting the closing of said switch when only one of said circuits is energized.

15 26. In combination with two alternating current circuits, switching means for interconnecting said circuits, a synchronoscope controlling said switching means, said synchronoscope including a rotary element and means for rotating 20 the same in one direction or the other depending upon the relative frequencies of said circuits, and means for indicating the direction of rotation of said element comprising a pivoted lever having frictional engagement with said element 25 whereby it is tilted in a direction determined by the direction of rotation of said element, and electric indicating circuits selectively controlled by said lever in opposite positions thereof.

30 27. In a control system, a switching device for interconnecting two sources of alternating current, a relay, means operative to energize said relay at a predetermined phase angle in advance of phase coincidence provided the difference in 35 the frequency of said sources is less than a predetermined amount, a maintaining circuit including a switch closed by said relay for maintaining said relay energized, a circuit over which said relay operates said devices, and means for 40 opening said maintaining circuit if the phase difference between said sources increases beyond a predetermined amount before the operation of said device is completed.

28. In a control system, a switching device for 45 interconnecting two alternating current sources, means for testing said sources to determine the difference in their frequencies, means responsive when the frequencies are found to differ by any amount less than a predetermined amount for initiating the operation of said device, means for insuring that such operation is initiated before said sources reach phase coincidence, and means incapable of initiating the operation of said device but operative to continue such operation to completion after said initiating means has become ineffective, provided the phase difference between said sources does not increase more than a predetermined amount before such operation has been completed.

55 29. In a system for interconnecting two alternating current power lines, a switching device for connecting said lines, a control switch, means responsive to the operation of said control switch for operating said device if the said lines have the same frequency and do not differ in phase by more than a predetermined amount, means for rendering said first means inoperative if said lines differ in frequency, and means alternative to said first means for testing the frequency difference between said lines each time they approach phase coincidence and for effecting the operation of said device substantially at phase coincidence when said frequency difference falls below a predetermined amount.

30. In a system for interconnecting two alternating current circuits when the phase and frequency differences are within predetermined limits, a main switching means for connecting said circuits together, two alternative closing means selectively operated in accordance with the condition of the frequency and phase relation of the voltages in said circuits for operating said main switching means, one of said closing means being operative when the frequencies remain the same for more than a predetermined time provided the phase difference does not exceed a predetermined amount, the other of said closing means being operative when the frequencies remain the same for less than said predetermined time and under a different condition of phase difference, and means controlled in accordance with the phase and frequency differences in said circuits for bringing about the selective operation of said two closing means as set forth.

31. In a control system, a switching device for interconnecting two alternating current sources, a rotatable element adapted to rotate at a speed dependent on the difference in the frequency of said sources, a starting switch for associating said element with said sources to render the same operative, means also rendered operative by said starting switch contingent on said element failing to start rotation for a predetermined time for initiating the operation of said switching device, and a second means for initiating the operation of said switching device in case said first means fails to operate due to rotation of said element, said second means being controlled jointly by said starting switch and by said element, and means including said element for insuring that said second means is operated at a time when the frequency difference is less than a predetermined amount and in advance of phase coincidence.

32. In a control system, the combination with a switching device for interconnecting two alternating current sources, of an automatic synchronizer for controlling said device, said synchronizer comprising a synchroscope motor supplied with power from said sources, a rotatable member supported on the shaft of said motor and driven thereby if the frequency of one of said sources is higher than the frequency of the other

source, means carried on said rotatable member for initiating the operation of said switching device, an auxiliary control member, a pivot for supporting said control member independent of said shaft, means including said rotatable member for moving said control member on said pivot, and means including said control member cooperating with the said means carried by said rotatable member for causing the operation of said device to be initiated in advance of phase coincidence.

33. In a control system, the combination with a switching device for interconnecting two alternating current sources, of an automatic synchronizer for controlling said device, said synchronizer comprising a synchroscope motor supplied with power from said sources, two relatively movable members, one of which is rotated by the shaft of said motor if the frequencies of one of said sources is higher than the frequency of the other source, means independent of said shaft for pivotally supporting the second of said members, means including the first of said members for moving the second member on its pivot, a circuit for initiating the operation of said device, and means including a part carried by the first of said members and a part carried by the second member cooperating therewith for causing said circuit to be closed in advance of phase coincidence.

34. In combination with two alternating current circuits and a switch for connecting the circuits, control means for said switch including means responsive to the frequency and phase difference of the voltages in said circuits at the switch and connected and arranged to be effectively energized for effecting the closing of said switch only when the frequencies of the voltages of the said two alternating currents circuits have remained in synchronism and within a predetermined phase difference during a predetermined time interval, and also including means for preventing closing of the switch if the voltages in the circuits assume a frequency difference during said interval, and also including means for closing said switch when said responsive means is effectively energized by only one of said circuits and the other circuit is de-energized.

ERICK PEARSON.
